UNITED STATES PATENT OFFICE.

THOMAS SANDERS HARRIS AND JOSEPH PENELL MORGAN, OF ELDREDGE, TEXAS.

POTATO SCREENING AND SORTING MACHINE.

1,161,211.

Specification of Letters Patent. Patented Nov. 23, 1915.

Application filed December 14, 1914. Serial No. 877,255.

To all whom it may concern:

Be it known that we, THOMAS SANDERS HARRIS and JOSEPH PENELL MORGAN, citizens of the United States, residing at Eldridge, in the county of Colorado and State of Texas, have invented certain new and useful Improvements in Potato Screening and Sorting Machines; and we do hereby declare the following to be a full, clear, and exact description of the invention, such as will enable others skilled in the art to which it appertains to make and use the same.

This invention relates to potato screening and sorting machines, and has for one of its objects the provision of a machine of this character, which is simple in construction, efficient in operation, and which can be manufactured at a nominal cost.

A further object of this invention resides in the provision of a machine for efficiently screening and sorting potatoes, and which delivers the smaller potatoes at the side of the machine, while the larger potatoes are delivered at either end of the machine as desired, thereby facilitating the operation of the machine.

A still further object of this invention resides in the provision of a screening and sorting machine, provided with means for 30 tilting the upper screen member in either direction as desired, for discharging the contents thereof into a sack suspended at either end of the machine, to provide for the continuous and uninterrupted operation 35 of the machine. And a still further object of this invention resides in providing the ends of the upper screen member with doors, provided with means for automatically opening the same upon the tilting of the 40 screen member to provide for the discharge of the contents thereof from either end, the doors closing by gravity upon the return of the screen member to horizontal position.

Other objects and advantages of this invention will be hereinafter more clearly set forth in the specification, defined in the claims, and illustrated in the accompanying drawings, in which,

Figure 1 is a vertical perspective view of 50 the entire machine. Fig. 2 is a side view of the same as it appears in dumping operation. Fig. 3 is an end view, showing the manner of mounting the upper screen frame in the swinging devices. Fig. 4 is a perspective view of one of the doors detached 55

from the upper screen frame, showing the means employed for pivotally mounting the doors at the ends of the screen frame, and also for automatically opening the doors.

Referring to the drawings, the machine 60 consists of a stand or frame built upon the four legs or corner posts A, at the upper ends of which are secured the top rails B, having their ends projecting outwardly beyond the corner posts A so as to allow space 65 thereunder for hanging sacks upon the hooks B' upon the ends of the rails B. One-half way down the corner posts A are secured the side rails C, and also secured near the bottom ends of the corner posts A are the side 70 rails D.

The sides of the frame are connected together at the top and the bottom by the end rails E, and beginning at each of the upper end rails, and extending inwardly and downwardly for approximately one-third of the length of the frame, are the small mesh screens F. The screens F sift the dirt from the smaller potatoes and direct the potatoes toward the center of the frame where they are deposited upon another screen G of larger mesh than the screens F, and which is sloped downwardly and laterally of the frame so as to direct the smaller potatoes 80 into a sack which is hung upon the hooks G' 85 arranged on the end of the screen G at the side of the frame.

At each side of the frame, and substantially one-third of the distance from each end thereof, are mounted two vertical sliding standards H, which are arranged directly opposite each other, making a total of four standards, and are connected together in pairs at their centers by the cross bars I, which normally rest upon the side rails C. 90 The standards H are held in operative position upon the side rails B and C by the guides J. The top of the standards H project above the side rails B and have mounted therein the upper swinging screen frame K through the medium of two substantially U-shaped iron rods L, which are pivotally mounted in the upper ends of the posts H and adapted to swing backward and forward. The screen frame K is provided with the screen K', which is of larger mesh than the screen F and G, for separating the larger potatoes from the smaller potatoes. 105

Upon each side of the screen frame K is secured a small block M adapted to bump 110

against the sliding standards H thus giving the screen frame K a sudden stop so as to thoroughly screen the potatoes.

- 5 Positioned at the bottom of the frame, at each end thereof, are the foot levers N, which have their central portions bent to provide shafts pivotally mounted upon the side rails D, and the center rails O, through the medium of the bearings P. The inner 10 ends of the foot levers N are connected to the centers of the cross bars I of the sliding standards H, through the medium of the rods Q, so that, pressing the outer end of one of the foot levers N downwardly, causes 15 two of the sliding standards H to be raised upwardly, thereby lifting one end of the screen frame K, and at the same time lowering the other end thereof, in the manner shown in Fig. 2.
- 20 The screen frame K is provided at its ends with the doors R, provided with the small iron rods S, provided with the eyes S' for pivotally attaching the doors R to the inner sides of the screen frame K. The rods S are 25 bent to extend downwardly over the faces of the doors and are fastened thereto by the use of the wood screws T, and continue downwardly therefrom below the doors R and are bent outwardly and then inwardly, 30 providing the feet U, which almost touch the upper rails of the frame, so that, when one end of the screen frame K is lowered, the feet U of the rods S engage the upper rails of the frame and forces the respective 35 door R to open, thus allowing the potatoes to pour into one of the open bottom troughs or spouts V, formed in the projected ends of the top rails B, and thence into a sack suspended beneath the trough or spout V 40 upon the hooks B'. When either of the levers N is released, the screen frame K will return to its normal horizontal position, and the doors R will close, by gravity. Upon the outer sides of the screen frame K are 45 provided the handles W for reciprocating the frame.

In operation, the potatoes are poured into the upper screen frame K, and the person or persons operating the machine grasps the handles W and reciprocates the frame K rapidly back and forth in the swinging rods L, with the blocks M striking against the standards H at each side thereof to cause a sudden jarring of the frame K to facilitate 50 the screening of the potatoes. During this movement of the frame K, the larger potatoes are separated from the smaller potatoes and dirt, the screen K' being of sufficient size mesh to accomplish this result. The 55 smaller potatoes and the dirt then fall upon the sloping screens F and G, which are formed of a mesh sufficiently small to separate the smaller potatoes from the dirt, which latter falls to the ground or floor, the 60 smaller potatoes being directed by the slop- 65

ing screens F and G toward the discharge end of the screen G where the smaller potatoes are delivered into a sack hung upon the hooks G' thereat. When this step in the screening operation has been completed, the 70 operator presses the outer end of one of the levers N downwardly with his foot, which rocks the lever N in the bearings P and elevates the inner end of the lever, which through the medium of the connecting rod Q and the cross bar I connecting one pair of the standards H, lifts these standards upwardly to elevate one end of the frame K and thus lower the opposite end thereof, the 75 rod L of the other pair of the standards H 80 acting as a pivot, whereby the feet U of the rods S, which are secured to the door R at the lowered end of the frame, will contact with the upper rails of the machine and automatically open the door R, and the larger 85 potatoes in the frame K are now discharged into the adjacent spout V, and into the sack hung upon the hooks B' therebeneath. This 90 operation may be successively repeated as long as desired, and without interruptions, in 95 view of the fact, that when a bag at one end of the machine is filled with the larger potatoes, the operator manipulates the opposite lever N for tilting the frame K in the opposite direction for filling a bag at the other 100 end of the machine, while the first bag is being removed and replaced by an empty bag, whereby the operation is continual.

We are aware that there are other potato screening and sorting machines made, but 100 we do not believe there is any machine more thoroughly constructed so as to suit the demand of the grower and shipper as our machine. First, for its absolute screening; second, for its speedy and convenient dumping device; third, for its lightness in weight, thus enabling the machine to be moved as desired, by one or two men.

Having described our invention, what we 110 claim as new and desire to secure by Letters Patent, is:—

1. In a vegetable separator, the combination with a supporting frame, of a stationary frame arranged upon said supporting frame, sliding standards arranged upon said supporting frame, a movable frame arranged upon said sliding standards above said stationary frame, and means for actuating said sliding standards for tilting said movable frame in either direction for discharging the contents thereof from either end.

2. In a vegetable separator, the combination with a supporting frame, of a stationary frame arranged upon said supporting frame, sliding standards arranged upon said supporting frame, a movable frame arranged upon said sliding standards above said stationary frame, means for actuating said sliding standards for tilting said mov- 120 125 130 135 140 145 150 155 160 165 170 175 180 185

able frame in either direction for discharging the contents thereof from either end, and automatically operable doors pivotally mounted in the ends of said movable frame.

5 3. In a vegetable separator, the combination with a supporting frame, of a stationary frame arranged upon said supporting frame, sliding standards arranged upon said supporting frame, a movable frame arranged upon said sliding standards above said stationary frame, means for actuating said sliding standards for tilting said movable frame in either direction for discharging the contents thereof from either end, automatically operable doors pivotally mounted in the ends of said movable frame, and means within said stationary frame for discharging the contents at one side thereof.

10 4. In a vegetable separator, the combination with a supporting frame, a stationary frame arranged upon said supporting frame, the side rails of said stationary frame projecting outwardly beyond the ends of said supporting frame, spouts arranged in the

projecting ends of said side rails, means 25 upon said spouts for suspending a sack therebeneath, means within said stationary frame for discharging its contents at one side thereof, means for suspending a sack thereat, a plurality of standards slidably 30 mounted upon said supporting frame, swinging rods pivotally mounted in the upper ends of said standards, a movable frame mounted in said swinging rods above said stationary frame, automatically operable 35 doors pivotally mounted in the ends of said movable frame, and means within said supporting frame for actuating said standards for tilting said movable frame in either direction and to automatically open one of 40 said doors for discharging the contents of said movable frame in the adjacent spout.
